CLAIM

The ornamental design for a sash lock as shown and described.

DESCRIPTION

FIG. 1 is a top view of the sash lock of the present invention where the hood of the sash lock covers the keeper.

FIG. 2 is a front view of the sash lock of the present invention showing the lock and the keeper.

FIG. 3 is a bottom view of the sash lock of FIG. 1.

FIG. 4 is a rear view of the sash lock of FIG. 1.

FIG. 5 is a left side view of the sash lock of FIG. 1.

FIG. 6 is a right side view of the sash lock of FIG. 1.

FIG. 7 is a rear perspective view of the sash lock of FIG. 1.

FIG. 8 is a front perspective view of the sash lock of FIG. 1.

FIG. 9 is a top view of an alternative embodiment of the sash lock of the present invention where hood of the sash lock does not cover the keeper.

FIG. 10 is a front view of the sash lock of FIG. 9.

FIG. 11 is a bottom view of the sash lock of FIG. 9.

FIG. 12 is an end view of the sash lock of FIG. 9.

FIG. 13 is a left side view of the sash lock of FIG. 9.

FIG. 14 is a right side view of the sash lock of FIG. 9; and,

FIG. 15 is a perspective view of the sash lock of FIG. 9.
